ISAAC F. WOODWARD, OF PHILADELPHIA, PENNSYLVANIA.

Letters Patent No. 64,730, dated May 14, 1867.

IMPROVEMENT IN WATER-INDICATORS FOR BOILERS.

The Schedule referred to in these Letters Patent and making part of the same.

TO ALL WHOM IT MAY CONCERN:

Be it known that I, ISAAC F. WOODWARD, of Philadelphia, Pennsylvania, have invented an improved Water-Indicator for Steam Boilers; and I do hereby declare the following to be a full, clear, and exact description of the same, reference being had to the accompanying drawing, and to the letters of reference marked thereon.

My invention consists of a glass tube, having a closed top and lower open end communicating with the steam-space of a boiler, in combination with an indicating rod arranged to slide in the tube, and connected to or controlled by a float, all substantially as described hereafter, so that the exact height of the water in the boiler can always be ascertained without the aid of the objectionable stuffing-boxes which have been hitherto deemed indispensable adjuncts to indicators of this class.

In order to enable others skilled in the art to make and apply my invention, I will now proceed to describe a mode of carrying it into effect. On reference to the accompanying drawing, which forms a part of this specification—

Figure 1 is a sectional view of my improved water-indicator for steam boilers.

Figure 2, an exterior view of the same.

Figure 3, a transverse sectional plan on the line 1-2, fig. 1; and

Figure 4 a modification of part of the instrument.

A represents part of the upper portion of the shell of a boiler, into which is screwed a hollow stud, B, and in the upper portion of the latter is formed an enlargement or recess, into which is screwed the follower D, and between this follower and the bottom of the recess intervenes a packing-ring, e. E is a glass tube, closed at the top and open at the bottom, its lower end passing through the follower D, packing e, and stud B into the boiler, so as to communicate with the steam-space of the same. The tube may be confined to its place either by the simple pressure of the packing around it, or an enlargement or flange may be made on the tube and confined with the packing by the follower D. F is a float, having a tube, f, for the admission of a screw-rod, G, which is provided with nuts h, one above and the other below the float, so that the latter may be adjusted on the rod. At the upper end of the rod G is a disk, m, and below the latter a similar disk, n, both disks being arranged to slide freely in the interior of the glass tube, and being so much smaller than the latter that the steam can have free access to every part of the interior of the tube. Small pieces of metal, of the form shown in fig. 4, may be used in place of the disks, so as to serve as guides for the rod during its movements, and at the same time permit the steam to circulate freely in the tube. Either to the follower D or stud B is cast, or otherwise secured, the index-plate H, which, in the present instance, is made of the shape best observed on reference to fig. 3, one half of the glass tube being contained within a vertical groove made in the plate by bending the same, as shown, and flanges t t being formed one on each edge of the plate, on which flanges are made such marks or figures as may be deemed most appropriate for indicating the height of the water in the boiler, for the float must be so adjusted on the rod G, in respect to the disk m and the marks on the plate, that the coincidence of this disk with a given mark will indicate the precise height of the water in the boiler. On the top of the plate H, and covering the end of the groove in the same, is a plate, y, against which the upper end of the glass tube bears, so as to prevent the latter from being forced upwards by the steam. A small strip of gum-elastic or other like material may be interposed between the plate y and top of the glass tube.

In the present instance there are but three index marks—1, 2, and 3—on the plate H. When the disk coincides with the mark 2 the water is at an appropriate height, but when the disk falls below this mark it indicates a want of water, and when it approaches the mark 1, determines the fact that there is a superfluity of water within the boiler. As the front of the tube is exposed to view, the position of the disk m in respect to these marks can be easily observed.

Many devices, in which a float is a prominent feature, have been devised for indicating the height of water in a boiler, but in all cases within my knowledge the movement of the float has been communicated to some indicating object through the medium of a rod or wire passing through a stuffing-box in the boiler, a well-known objectionable feature, to dispose of which has been the main object of my invention. In my improved indicator there are no joints or stuffing-boxes to interfere with the delicate operation of the only moving object, which is the rod G and its float, and this moving part, being contained within the steam-space of the boiler, has full

edom of action, and cannot possibly fail to perform its duty with the greatest certainty. The rod G may be continued so far below the float as to come in contact with the bottom of the boiler when the latter is empty, thereby preventing the entire withdrawal of the indicating portion of the rod from the tube. It will be evident that the index-plate, and the appliances for securing the open end of the tube to the boiler, may be altered or modified without departing from the main feature of my invention.

I claim as my invention, and desire to secure by Letters Patent—

A glass tube, having a closed top and lower open end communicating with the steam-space of a boiler, in combination with an indicating-rod arranged to slide in the tube, and connected to or controlled by a float, all substantially as and for the purpose herein set forth.

In testimony whereof I have signed my name to this specification in the presence of two subscribing witnesses.

ISAAC F. WOODWARD.
